UNITED STATES PATENT OFFICE.

PETER RANK, OF ST. PAUL, MINNESOTA.

STRIKING-BAG SUPPORT.

1,066,437.

Specification of Letters Patent:

Patented July 1, 1913.

Application filed October 7, 1912. Serial No. 724,260.

To all whom it may concern:

Be it known that I, PETER RANK, a citizen of the United States, residing at St. Paul, in the county of Ramsey and State 5 of Minnesota, have invented a new and useful Improvement in Striking-Bag Supports, of which the following is a specification.

This invention relates to an improved striking bag support and has for its primary object, simple and inexpensive construction which can be easily made from 10 ordinary stock material and which is strong and durable in use.

In the accompanying drawing forming 15 part of this specification, Figure 1 is a perspective of my invention; Fig. 2 is a section through one of the supporting arms and the ring showing the method of securing said parts together; Fig. 3 is a perspective of a spring washer which is used 20 between the bolt and supporting arms as illustrated in Fig. 2 and Fig. 4 is a detail, part of which is shown in section.

In the drawing 2 represents a ring which 25 is supported in a horizontal plane and against which the striking bag 3 is adapted to impinge when in action. The ring 2 is supported by horizontal bracket arms 4 and 5 and an upwardly slanting arm 6. Near 30 the center of the ring is a union 7 with which the arms 4, 5 and 6 are connected by threading, said arms 4 and 5 being arranged at right angles to each other and secured to the ring by bolts 8. The arms 4 35 and 5 are bent obliquely at 9 to extend backwardly to the wall or other supporting object to which their ends are secured by bifurcations 10. In alinement with the portions of the arms 4 and 5 which are ar- 40 ranged at right angles, are two oppositely arranged arms 11 and 12 which are secured into the union 7 by threads and their outer 45 ends fastened to the ring by bolts 13. A spring washer 14 (see Fig. 3) is placed be- 50 tween the heads of the bolts 8 and 13 and the arms which they secure to the ring for the purpose of holding the bolts tight. The arm 6 is fastened into the upper central portion of the union 7 by threads and is 55 bent back to the support to which the arms 4 and 5 are adapted to be secured. The arms 4, 5 and 6 are adapted to support the ring rigidly from overhead, allowing the striking ball free play below.

55 Into the lower central portion of the union 7 a depending arm 15 is secured by

threads and to the lower extremity of said depending arm a centrally apertured cup 16 is secured which is threaded to the arm 15 and adapted to hold a bushing 17 made 60 of relatively soft material such as wood. The striking ball 3 is hung from the lower extremity of arm 15 by its cord 18, the upper end of which is knotted at 19 above the bushing 17 in the cup 16, said bushing hav- 65 ing a centrally disposed passage 20 in which the cord is free to play or swivel. The bushing has a nipple 21 projecting downwardly through the cup, the inner sur- 70 face of said nipple being curved at 22 to prevent abrading of the rope 18 by the swing- ing action of the ball.

The supporting parts described composed of the ring, and arms are adapted to be made out of ordinary stock pipe or tubing 75 which is a convenience and an advantage in constructing the apparatus.

In use the arms 4, 5 and 6 are adapted to be secured to a support such as a wall by inserting screws through the bifurcations 80 10 and the flange 23, the ring 2 being ad- justed in a horizontal plane. The striking ball is then secured by its cord in the swivel end of the arm 15, the cord being adjusted in length so that the ball will swing against 85 the ring when in action.

In accordance with the patent statutes I have described the principles of opera- 90 tion of my invention together with the apparatus which I now consider to represent 95 the best embodiment thereof but I desire to have it understood that the construction shown is only illustrative and that the in- vention can be carried out by other means and applied to uses other than those above 95 set forth within the scope of the following claim.

Having described my invention, what I 100 claim as new and desire to protect by Let- ters Patent is:

A striking ball support, comprising, in combination, a horizontal ring, a union con- 105 centric to said ring, arms radiating from, and threaded to said union and secured to the upper portion of said ring, part of 110 said arms projecting from said ring and forming brackets adapted to be secured to a supporting object, an overhead arm threaded down into said union and extending back and above said ring and adapted to be secured to a supporting object, a down- wardly extending arm on said union, a cup

secured over the lower extremity of said downwardly extending arm, a passed bushing secured by said cup to the lower end of said downwardly extending arm and 5 extending downwardly through said cup, a striking ball and a flexible support on said ball having an end secured in and passing freely through said bushing.

In testimony whereof, I have signed my name to this specification, in the presence 10 of two subscribing witnesses.

PETER RANK.
